CHILD'S ANKLET

Anthony Liem, Pasadena, Calif.
(1800 Huntington Drive, San Marino, Calif. 91108)

Filed Mar. 20, 1967, Ser. No. 6,287

Term of patent 14 years

(Cl. D45—4)

Fig. 1

The characteristic feature of my design resides in the combination of the anklet and of the series of stylized dogs positioned thereon as shown.

I claim:

The ornamental design for a child's anklet, substantially as shown and described.
